UNITED STATES PATENT OFFICE.

WILLIAM O. BLOOM, OF WEST BOYLSTON, MASSACHUSETTS.

RUG-HOLDER.

1,370,727.

Specification of Letters Patent.

Patented Mar. 8, 1921.

Application filed September 8, 1919. Serial No. 322,463.

To all whom it may concern:

Be it known that I, WILLIAM O. BLOOM, a citizen of the United States, residing at West Boylston, in the county of Worcester 5 and State of Massachusetts, have invented a new and useful Rug-Holder, of which the following is a specification.

This invention relates to an attachment for or construction of rugs for preventing 10 their slipping on hardwood floors.

The invention is particularly designed for small rugs, although capable of use for rugs of all sizes. It is common experience that small rugs, especially when located on 15 hardwood floors, slip around very easily, giving annoyance by getting out of place, and also occasionally resulting in an accident. I am aware of the fact that attempts have been made to avoid this difficulty, but 20 so far as I am informed they are of an impractical nature.

The object of this invention is to provide an exceedingly simple, light, and inexpensive means for preventing or reducing the 25 danger of their slipping. I prefer to provide it in the form of an attachment which can be made and applied by the rug manufacturer, or can be purchased separately by the user and attached by him if desired.

30 Further objects and advantages of the invention will appear hereinafter.

Reference is to be had to the accompanying drawings, in which—

Figure 1 is a bottom plan view of a rug 35 showing a preferred embodiment of this invention applied thereto,

Fig. 2 is a transverse sectional view showing a rug right side up on a floor and illustrating the invention on a larger scale, on 40 the line 2—2 of Fig. 1, and

Figs. 3, 4 and 5 are views similar to Fig. 1 of modified forms of the invention.

In order to hold a rug in position on a floor, I place beneath it a device comprising 45 strands of non-slipping material which grip the floor. To keep them from moving relative to each other and the rug I may fasten the separate strands to the rug by suitable means, but I find it preferable to tie 50 these strands together so as to form a fabric or netting which is a complete device in itself capable of being thrown down on the floor beneath a rug and of being cut to any desired size to fit any rug. The strands 55 of the fabric have so many line contacts with the floor as to make slipping difficult

and they sink into the under surface of the ordinary rug enough to make it not absolutely necessary to fasten the two together. 60

In accordance with one embodiment of my invention, as illustrated in Fig. 1, I may apply to the rear surface of a rug a light and open fabric or netting 10 of strands of thread, yarn or cord and preferably the ordinary square mesh. The net is woven in any desired manner, the knots tying the strands together being conventionally illustrated at 11. In certain cases these knots 11, as illustrated in Fig. 2, may 70 constitute comparatively hard and rigid projections spaced apart on the fabric and form the main non-slipping contacts with the floor.

The strands or netting may be made of 75 non-slipping material, but I find it preferable to utilize the ordinary fabric materials and coat them with such non-slip substances as rubber, this operation being performed before or after the device has been 80 woven or made up into the desired form. This can be provided by dipping the net in it, although if desired the knots only or their lower surfaces may be supplied with 85 this coating. In such a case the knots constitute areas spaced apart on the fabric for reducing the propensity for slipping.

After the net is dried, a border 12 of 90 tape or other suitable material may be applied to its four edges, and if desired, this may be attached to the lower surface of the rug 13 near the edge. The tape can be sewed to the rug if desired, but I have indicated in Fig. 2, ordinary snap fasteners 14 for securing it in position. 95

In the form shown in Fig. 3 the attachment is made up of separated strands 18 each extending along a portion of the rear surface of the rug. These strands may be non-slipping throughout their entire areas 100 of contact with the floor, or they may have rubberized areas on projecting knots 19, tied in the strands. I have shown an end tape 20 to which the strands are connected, and which is attached to the rug. In Fig. 105 4, the same arrangement is shown but without the knots.

I prefer to have the strands run longitudinally in both these forms and in either case they can be directly attached to the rug 110 without any tapes at the edges. Each strand is stretched taut and the slipping of the

rug is resisted by each one throughout its length.

I find that for any ordinary sized rug the fastening of the netting or strands to the rug at its edges with or without the tape as above described is sufficient because the whole attachment is light and flexible, and the strands or the knots in addition to the above function also project into the bottom of the rug and tend to hold the non-slip device in proper position at all points, but I do not wish to limit myself to fastening it only at the edges, or to fastening it to the rug at all.

15 In Fig. 5 I have shown a form of the invention in which a light fabric or close meshed netting 21 is attached to the rug and provided on the bottom with rubberized areas preferably formed of pieces 22 of 20 rubber or rubberized fabric spaced apart for lightness.

In use, it is found that the light fabric or collection of strands extending throughout substantially the entire lower surface of the rug adds practically nothing to its weight and detracts in no way from its wearing or other qualities, but it furnishes a large number of small areas spaced apart but engaging the floor under substantially all parts of 30 the bottom surface of the rug, and constitutes means for retarding any slipping action which may be imparted to the rug. The non-slipping character of these areas acts in an obvious manner to assist in the 35 above described function, and it has been demonstrated that even a very small rug provided with a backing of this character will not slip even when subjected to a sudden force substantially parallel with the 40 floor, and of a strength as great as is likely to be applied in the common usage of the rug.

Although I have described and illustrated only one form of the invention, I am aware 45 of the fact that many modifications can be made therein by any person skilled in the art without departing from the scope of the invention as expressed in the claims. Therefore I do not wish to be limited to all the 50 details of construction herein shown and described, but what I do claim is:—

1. As an article of manufacture, a non-slipping attachment for a rug comprising a detachable netting adapted to extend substantially throughout the area of the bottom surface of the rug and having projections adapted to engage the floor for preventing the rug from slipping.

2. As an article of manufacture, an attachment for the lower surface of a rug comprising a square mesh netting made up of crossing cords having knots at their crossing points constituting projections, said netting being supplied with a coating of non-slipping composition.

3. As an article of manufacture, an attachment for the lower surface of a rug comprising a netting having knots constituting projections, said netting being supplied with a coating of non-slipping composition and 70 having a border of tape for attachment to the rug.

4. The combination with a rug, of a netting detachably mounted on the under side thereof, said netting being dipped in a rubber composition to render it non-slipable. 75

5. The combination with a rug, of a non-slipping attachment applied to the bottom thereof comprising a netting having knots constituting projections adapted to hold it 80 in position on the bottom of the rug and also to hold the rug in position on a floor.

6. The combination with a rug, of a non-slipping attachment separably connected with the bottom surface thereof made up of 85 crossing strands, the crossing points being provided with spaced areas having non-slipping lower surfaces.

7. The combination with a rug of a non-slipping attachment for the bottom surface 90 thereof made up of spaced separable strands provided with frictional lower surfaces.

8. The combination with a rug, of a light member attached to the rear surface thereof and provided with spaced areas on the bottom free from the rug and treated with a composition to reduce the propensity to slip on a floor. 95

9. The combination with a rug, of a detachable anti-slipping attachment for the 100 floor surface thereof made up of light flexible strands spaced apart and provided with means for frictionally engaging the surface of the floor.

10. The combination with a rug, of an attachment therefor comprising light flexible strands spaced apart connected at both ends to the rug, separate at intermediate points, and provided with surfaces adapted to frictionally engage the surface of the floor. 105

11. The combination with a rug, of light, flexible, members extending along the rear surface thereof, free to move with respect to said surface and treated with a composition to reduce the liability of slipping on the 115 floor.

12. A device to prevent rugs slipping on floors comprising non-slip strands separated from the rug, means for connecting them together, and means for fastening them to 120 the underside of a rug.

13. As an article of manufacture, an attachment for the under surface of a rug comprising a plurality of connected strands free from the rug throughout most of their 125 length and having a non-slipping surface to engage the floor.

In testimony whereof I have hereunto affixed my signature.

WILLIAM O. BLOOM.
